Specification for Design.

Patented Mar. 8, 1921.

Application filed August 23, 1920. Serial No. 405,520. Term of patent 3½ years.

To all whom it may concern:

Be it known that I, LOTTIE E. FREEMAN, a citizen of the United States, residing at Boston, in the county of Suffolk and State of Massachusetts, have invented a new, original, and ornamental Design for a Child's Garment, of which the following is a specification, reference being had to the accompanying drawing, forming part thereof.

In the drawings, Figure 1 is a front elevation of a child's garment showing my new design, and Fig. 2 is a rear elevation of the same.

I claim:

The ornamental design for a child's garment, as shown.

LOTTIE E. FREEMAN.
